STABILIZING SUPPORTING DEVICE FOR BODIES ON WATER

Filed March 2, 1932

UNITED STATES PATENT OFFICE

SAMUEL FEIR, OF BROOKLYN, NEW YORK

STABILIZING SUPPORTING DEVICE FOR BODIES ON WATER

Application filed March 2, 1932. Serial No. 596,250.

This invention relates to devices for supporting bodies in a stabilized relation on liquids, and has particular application to devices of this general character applicable to human beings.

One object of the invention is to provide a device of the nature set forth having improved means for uniformly supporting a body on a liquid by creating a plurality of distributed areas of support so arranged as to maintain the body in predetermined or upright position.

Another object of the invention is the provision of a device of the class alluded to having a plurality of buoyant elements disposed in spaced relation to each other around a body and in preferably close coaction therewith, certain of said elements being so interrelated as to produce a streamlined effect facilitating movement of the body through or along a fluid medium; and another object is to furnish a device as aforementioned having improved means associated therewith which may be adapted for actuating or propelling the body, and which may, if desired, afford a supplemental buoyant force thereto.

A further object of the invention is to provide a device of the character described having improved means for interengaging the buoyant elements, and whereby individual attachment of said elements may be obtained, if desired; and wherein the elements may be easily and conveniently applied to a body and may be connected therewith as a unit if required, with said elements affording ample opportunity for different movements of the body and support thereof as in upright, sitting or floating positions, without impeding any desired motions of the limbs; and said device being relatively light in weight, neat in appearance, inexpensive to manufacture and durable, reliable and efficient to a high degree in use; said device being especially applicable for use in rough seas; together with an improved method for safeguarding people against drowning while permitting them to travel along the water.

Other objects and advantages of the invention will become apparent as the specifications proceeds.

With the aforesaid objects in view, the invention consists in the novel combinations and arrangements of parts hereinafter described in their preferred embodiments, pointed out in the subjoined claims, and illustrated on the annexed drawing, wherein like parts are designated by the same reference characters throughout the several views.

In the drawing:

Figure 1 is a view in front elevation of a device embodying the invention, showing the same in upright position.

Fig. 2 is a side view thereof in floating position.

Fig. 3 is a top plan of the device with certain parts removed.

Fig. 4 is a bottom plan view of a paddling device embodying a feature of the invention.

Fig. 5 is a top plan view of a modified device.

The advantages of the invention as here outlined are best realized when all of its features and instrumentalities are combined in one and the same structure, but, useful devices may be produced embodying less than the whole.

It will be obvious to those skilled in the art to which this invention appertains, that the same may be incorporated in several different constructions. The accompanying drawing, therefore, is submitted merely as showing the preferred exemplification of the invention.

Generally described, this invention provides a means for effectively supporting bodies of any kind in or on different fluid mediums preferably in uniformly stabilized relation. More particularly, the invention refers to devices for use with animate bodies, such as human beings in liquids such as water. Each of said devices may include a plurality of buoyant elements of any suitable or well known character, as, for instance, hollow thin walled members which are closed against entrance thereinto of the liquid sustaining medium. These members may be of different sizes, shapes, materials or construction, and it is sufficient that they are light in weight and so arranged and constructed individually and collectively as to facilitate at-

tainment of the objects in view. The invention resides principally in so correlating these members and in so associating the same with the person as to support the same in a stabilized position, this latter term having reference to the maintenance of the person in any required relation, for example, in upright or other position, except in so far as the person may desire to change his position, and then to permit the changed position to be readily maintained independently of or under the control of the person. Moreover, the device may be so arranged, as by streamlining or otherwise of individual members or groups thereof or both, as to facilitate ease or freedom of movement of the person along the water. Specifically, the device may include a plurality of the buoyant members, such as ball floats, of relatively large diameter disposed in spaced relation to each other around the body of the wearer in close proximity thereto, at a point intermediate the ends of the body, as at the waist thereof. Two of said balls may be arranged in front of the wearer, one being adjacent to each side of the body and two arranged at the back of the wearer in a corresponding manner. Hence the front and rear balls provide supports or pontoons elongated transversely of the wearer's body and in the direction of normal forward movement of said body; at the same time, said balls afford support to the body at every possible direction, whereby the person may freely safely turn in any direction, and be safeguarded against overturning by a powerful wave or the like. Other buoyant elements, such as ball floats, preferably of relatively small size may be disposed along the head, or back or arms, or any combination thereof, and anywhere else on the body as may be required, affording one or more additional localized or regional distributed supporting means of any auxiliary nature. Thus the auxiliary supporting means may be regarded as in the nature of providing forces along one or a plurality of spaced lines elongated along the wearer's body. The various buoyant members may be interengaged as by connection with a means extending around the wearer's body, such as a suit that may be waterproof, if desired, or strap or chain elements as may be feasible. This device is to be distinguished from ordinary floats or life belts which are ineffective to maintain a person in upright position. By means of this invention, a person can remain upright, and use his feet to propel him along the water, or maintain a sitting or floating position. Paddle-like devices may be attached to the limbs or constitute parts of the wearer's shoes, and may be of buoyant character, and so arranged as to permit a propelling action by a substantially normal to and fro movement of the legs as in walking.

65 Referring in detail to the drawing, 10 de-

notes a device embodying the invention. The same may include a person's body 11, and a means 12 extending transversely thereof and projecting along the normal path of travel of said person for buoyantly supporting him. 70 By disposing said means intermediate the ends of the body, as at the waistline 13, the body is readily maintained upright, and freedom of movement of the limbs is afforded. The means 12 may include a plurality of 75 buoyant members 14 suitably spaced from each other around the body so as to stabilize the same from every possible direction. Specifically, four of said members may be provided, two arranged at the front in proximity to the sides of the body and two similarly arranged at the rear of the body. Thus each pair of front and rear members provides an elongated buoyant support 15 which permits easy movement of the person through the 80 water.

While each buoyant member 14 may be made in different shapes and of different materials, it will suffice to point out one particular embodiment. Each buoyant member may be similarly constructed as a hollow ball, for instance, that may be made of a thin light material, flexible or rigid in character, and may consist of metal. The members 14 may be evacuated but are preferably air filled to avoid undue strains thereon and by reason of their spherical form, are well adapted to take up any stresses that may occur. These members are preferably relatively large, say 15 inches in diameter, but they may be larger or 90 smaller according to the buoyant forces required.

For closely engaging the buoyant members with the person's body, any suitable means may be provided, such as elongated 105 tension elements in the nature of chains or straps. For example, a belt 16 may extend around the wearer's body, and supplemental straps 17, 18 may extend respectively upward therefrom over the shoulders and downward along the legs and around the feet. The straps 18 may be secured by straps 19, 20 extending around the legs.

For connecting the buoyant members 14 with the belt 16, any feasible fastening means 115 may be used, acting for instance, at the points 21. These fastening means may be permanent or detachable in nature, and may consist of strong snap fasteners of any conventional nature. Hence the buoyant members 120 may be connected as desired, and in any case are securely maintained on the belt.

It will be understood that, if desired, a suitable water tight suit 22 may be provided for the person, and while the buoyant members might be connected with the suit, they are preferably mounted as above described. The suit may be positioned below the strap members.

To afford additional support for the per-

son, a supplemental means 23 including a plurality of relatively smaller buoyant elements 24 disposed along the wearer's body may be provided. These elements may be of the 5 same general nature, construction and appearance as the elements 14, and are preferably arranged in one or more spaced rows extending, for instance, longitudinally of the wearer's body. Thus rows 25, 26 of the 10 elements may extend along the back and opposite sides of the wearer's head, respectively. These rows may be mounted in any suitable manner, as by being attached to a head covering 27, of waterproof, or any other character, 15 and which may be held in position by a chin strap 28. Other rows 29, 30, 31 of the elements 24 may extend respectively centrally along the front and back of the wearer, and along his shoulders and arms. The elements 20 24 may also be disposed elsewhere along the wearer's body and in different arrangements. The rows 29, 30, 31 may be mounted by being fixedly or detachably connected to any suitable means such as the suit 22 which will 25 have adequate strength for the purpose. By means of the elements 24, the person is adequately supported as in floating position, and his head reliably kept out of the water, and yet, due to the distribution of the elements 30 24, the weight thereof is fully distributed so that freedom of action is maintained, and the person is supported evenly in different positions.

To facilitate movement of the device or 35 person through or along the water, an actuating means such as paddle devices 32 may be associated with the limbs, and preferably with the wearer's legs. For instance, shoes 33 may be provided that may be waterproof 40 or not, and which may have buoyant members 34 that may be streamlined or so arranged as to act as paddles in the normal to and fro movement of the wearer's limbs as in walking. Specifically, the members 34 may be 45 connected at the sole portions of the shoes, and may consist of thin walled metal air tight devices, each being of triangular form with a front edge 35 and rear face 36 of large area, transversely convexed to afford efficient 50 paddling action. The heel portions of the shoes may have connected thereto elements 37 of any desired nature for maintaining an even level of the shoes with the members 34.

In Fig. 5 is shown a modification of the 55 invention which may in all respects be similar to the device 12 shown in Fig. 1, except that the buoyant members 14 are replaced by buoyant elements 38 that are arranged to accentuate the streamlined effect in the direction of normal travel of a person as shown by arrow 39. Thus a pair of the elements 38 60 may form a pontoon like device 40 that is especially well adapted for movement with little resistance through the water. Each 65 element 38 may have a curved free end 41,

and be of circular or other form in cross section, and with its inner or fixed end 42 relatively large in area and concaved or otherwise shaped to fit snugly the body of the wearer.

It will be appreciated that various changes 70 and modifications may be made in the device as shown in the drawing, and that the same is submitted in an illustrative and not in a limiting sense, the scope of the invention being defined in the following claims. 75

I claim:

1. A device for the purpose specified comprising a harness adapted to be secured about the body of a swimmer, said harness comprising a belt portion, a plurality of buoyant elements secured to said belt, a pair of shoulder straps attached to the belt portion at the front and at the rear of the swimmer's body, a pair of leg straps attached to said belt at the opposite sides of the body at one end 80 and attached at their other ends to the belt adjacent the front of the body, said leg straps passing down under the instep of the swimmer's foot and having spacing straps secured thereto approximately at the knee 85 of the swimmer and at the ankle portion of the leg, substantially as set forth.

2. A device for the purpose specified comprising a harness adapted to be secured about the body of a swimmer, said harness comprising a belt portion having a plurality of buoyant elements secured thereto, a pair of shoulder straps attached to the belt portion at the front and at the rear of the swimmer's body, a pair of leg straps attached to the said belt at the opposite sides of the body at one end and attached at their other ends to the belt adjacent the front of the body, said leg straps having spacing straps secured thereto 90 approximately at the knee of the swimmer 95 and at the ankle portion of the leg, said leg straps passing under the instep of the shoes of the swimmer, substantially as set forth.

3. A device of the kind described adapted to support a swimmer in the water comprising a belt having a plurality of relatively large buoyant elements or floats secured thereto and having shoulder straps secured at the front and back to support the belt and the buoyant elements or floats upon the body of the swimmer and having a plurality of leg straps secured at their outer ends to the belt at opposite sides of the body of the swimmer and having their inner ends attached to the belt adjacent the front of the swimmer's body, said leg straps passing down under the instep of the swimmer's foot and having spacing and securing bands about the leg of the swimmer adjacent the knee and other bands about the leg adjacent the ankle 100 portion, substantially as set forth. 105

In testimony whereof I affix my signature.
SAMUEL FEIR.
